UNITED STATES PATENT OFFICE

2,573,571

AUTOMATIC TEMPERATURE CONTROL
FOR DRIERSFrederick W. Howland, Rochester, N. Y., assignor
to The American Laundry Machinery Company,
Cincinnati, Ohio, a corporation of Ohio

Application December 5, 1947, Serial No. 789,968

5 Claims. (Cl. 34—45)

1

This invention relates to automatic temperature control devices for various types of drying devices which employ a stream of air as the drying agent. While capable of use on any such drier it has been more particularly designed for application to drying tumblers for either laundry or dry cleaning use, and has been so shown, solely for purposes of illustration.

The object of the invention is to provide improved means for automatically maintaining the stream of drying air at a preselected maximum temperature for a predetermined time and for then cooling the load by the introduction of cold air.

A further object is to maintain the desired maximum temperature by utilizing a mixture of hot and cold air for the drying stream and varying the proportions of the two in step with pending temperature variations.

Maximum temperature control is especially advantageous in the case of a dry cleaning tumbler, since it permits them to be operated at any appropriate safe temperature for silks, wools, or other materials, while the combination of time and temperature control affords both flexibility and safety in drying loads of various natures and sizes.

In the drawings, which represent one suitable embodiment of the invention, Fig. 1 is a front elevation, partly broken out and in section;

Fig. 2 is a right side elevation of the upper portion of the machine, also broken out and in section;

Fig. 3 is a front elevation of the control mechanism;

Fig. 4 is a detail sectional elevation, on a larger scale, on the line 4—4, Fig. 2;

Fig. 5 is a sectional elevation on the line 5—5, Fig. 4;

Fig. 6 is a section on the line 6—6, Fig. 4;

Fig. 7 is a section on the line 7—7, Fig. 4; and

Fig. 8 is a detail view, showing the temperature control dial and pointer.

The particular form of the drying machine, as a whole, is not important, as the invention may be applied to any form. That shown includes a main frame or casing 10 having a drying chamber 11 in which rotates an open ended foraminous drum or cylinder 12 rotated alternately in opposite directions by suitable mechanism conventionally indicated by the dotted lines at 13, Fig. 1, and entrance to which, for loading or unloading the machine, is by way of an end casing opening closed by a hinged door 10a.

Air for drying purposes is supplied to the cham-

2

ber 11 through two channels or passages—cold air, such as air at ordinary atmospheric temperature, through passage 14, and hot air through passage 15, in which are located one or several heaters or radiators, such as the finned steam pipes or members 16 through which steam is circulated by way of supply and discharge pipes 17, 18.

The air stream passes through the drying chamber, and thus over and around the work being agitated in the drum, and leaves the chamber through an outlet passage 19 leading to a power driven fan or blower 20 having a discharge conduit 21.

Within the cold air passage 14 are located several, two being shown, pivoted vanes or dampers 22, while three such dampers 23 are shown in hot air passage 15. As shown in Fig. 4, the shaft of each of the dampers is provided at one end with an arm 24, all arms being connected to a common link 25 mounted in a control casing 26 at the top front of the machine. The two sets of dampers 22, 23 are disposed in planes at right angles to each other, the arrangement being such that general endwise motion of link 25 simultaneously turns all dampers, but as each set opens the other set closes. A light tension spring 27 connected to an arm 28 on one damper normally biases all dampers to the positions shown in Fig. 4, with the cold air dampers closed and the hot air dampers open.

One damper shaft is provided with a pinion 29 meshing with a vertically slidable rack 30 guided in a support 31 and provided near its lower end with a side pin or abutment 32 lying above a roller 33 on one arm of a lever 34 pivoted at 35 and having a second arm extending out through a slot in the control casing wall, beyond which it is provided with a handle 34a for manual operation. This lever is biased to move clockwise in Fig. 4, by a spring 36 stronger than spring 27, but may be maintained in the position there shown by a pair of toggle links 37, 38 one pivoted to said lever and the other to the casing wall. By grasping handle 34a and lifting the lever, the toggle knuckle moves to or a little beyond dead center and the parts are stable in the position so shown until the toggle is broken.

This is accomplished by engagement with the toggles, at or near the knuckle thereof, of the end of an arm 39 mounted on the inner key end of a shaft 40 which is connected to a wind-up clock type timer, marked generally 41, provided on the casing front with a setting hand 42 having

a pointer 43 traveling over a time period indicating scale 44.

The timer requires no detailed illustration or description. It is of a common type, readily available on the open market. By turning the setting hand to any value indicated on the dial scale, say five minutes, the arm 39, within the casing, is turned clockwise in Fig. 4 to a position there typified, away from the toggle members, and requiring the lapse of the desired time period (five minutes) before unwinding operation returns arm 39 sufficiently to break the toggles and cause roller 33 to move up.

Below the end of the rack bar 30 lies a pad 45 near one end of a lever 46 pivoted at 47 in the frame. Said lever, nearer its pivot is provided with a bottom pad 48 resting upon the inclined or sloping upper face of a wedge 49 slidable in and resting upon a channel form support 50 having a bent end ear 50a fixed to a tubular stationary member 51. Support 50 rests upon the upper movable end of an endwise expandable metal bellows 52 mounted at its lower end upon a support 53, the chamber within said bellows communicating by pipe 54 with the usual temperature responsive bulb 55, at any suitable point in the air stream within or beyond the drying chamber, and shown as located in outlet passage 21 from the blower.

Wedge 49 is slidably adjustable along its seat in its channel support, for which purpose it is connected by a link 56 to an arm 57 on shaft 58 which extends out through the front casing wall, beyond which said shaft carries an arm and pointer 59 traveling over a scale 60 graduated in temperature values. Arm 59 is provided on its rear face with a concealed spring ball latch 61 engageable with any one of several recesses 62 in the scale plate, to releasably hold the arm and other parts in any desired position.

The metal of which members 50, 50a is made is sufficiently resilient to permit member 50 to swing up and down as the bellows expand and contract.

Lever 46 is loaded, above, by the pressure of a suitable spring 63.

The control is also provided with a standard indicating thermometer member 64 mounted on the instrument board, as shown in Fig. 3, and communicating by a conduit 65 with a temperature sensitive bulb 66 also located in the outlet passage 21.

The operation is as follows:

Let us assume that the machine, with the control parts reset or in inoperative position, is ready for operation, with a load of material to be dried in the drying chamber, the door being closed, and with the mechanism 13 which alternately rotates the foraminous drum in opposite directions in operation.

The operator first sets the timer by turning the knob 42 and pointer 43 clockwise in Fig. 3 to a position indicating the length of the drying period, which of course includes the time necessary to bring the temperature up to the desired maximum value and the time during which it should be held at that value.

The operator then raises the control handle 34a to the position shown in Fig. 4, thereby straightening the toggles and moving the roller 33 down to its lowermost position, the parts so operated being stable in their new position because the toggle knuckle is at or a little beyond dead center, with the spring 36 fully effective.

Next he advances the handle 59 to a position

indicating on dial 60 the maximum temperature to be produced. This adjustment shifts the wedge 49 to the appropriate position, to wit, a position in which, when the desired maximum temperature is reached, the bellows 52 have expanded sufficiently to elevate the wedge and the lever 46, against the pressure of the loading spring 63 sufficiently to elevate the rack bar 30 and initiate closing movement of the hot air dampers and opening of the cold air dampers.

Of course, it is assumed that the steam is turned on to the heating coils 16, and the blower, of course, has been or is now started.

At the beginning of the operation the cold air dampers lie in fully closed position, and the hot air dampers in fully open position. Thus, at first, only hot air is supplied to the drying chamber through passage 15, from which it flows through the drying chamber and over and around the work in the drum therein, and thence to the outlet passage. The temperature gradually rises, and the moving current of hot air begins to carry away with it the vapor or mixture which it is desired to remove.

Finally the temperature reaches the maximum value to which the arm 59 has been set. At this particular moment pad 45 engages the lower end of the rack bar 30 and begins to elevate that bar, the rack and pinion causing simultaneous movement of all of the dampers and the links 25 connecting them. The hot air dampers move toward closed position and the cold air dampers toward open position. Thus the hot air stream is now reduced in quantity and is diluted with an increasing proportion of cold air, tending to prevent further rise of temperature. From this point on to the end of the drying period, the temperature responsive control bulb 55 and the bellows 52 actuated thereby, in cooperation with biasing spring 27, act as a governor, constantly moving the lever 46 up or down, as the case may be, to counteract any tendency of the temperature to rise above or fall below the desired maximum. Therefore, the maximum temperature is maintained through the remainder of the drying period, within a reasonably small variation therefrom.

At the end of the drying period, as determined by the clock mechanism 41 running down, arm 39 has reached and now engages the toggle members 37, 38, pushing the knuckle connecting them back across dead center to a position where the spring 36 completes the breaking of the toggles. This operation turns lever 34 in the clockwise direction Fig. 4, thereby suddenly and fully elevating the rack bar or rod 30, and fully turning the hot air dampers to closed position and the cold air dampers to open position. From this point on cold air alone is admitted to the drying chamber, the purpose being to cool the work as quickly as possible, because the drying operation is concluded.

The operator's attention is directed to the fact that the machine is ready for unloading by the movement of the handle 34a of lever 34 to its lowermost position, especially when that lever is made long enough so that its handle sticks out where it is easily visible. However, another simple arrangement to notify the operator includes a target 70, Fig. 4, mounted on a lever 71 pivoted at 72 on a frame support 73, a second arm of lever 71 being connected by a link 74 to one arm of lever 34. When the lever is in operating position the target occupies the full line position Fig. 4. But when the operation is concluded and cold air

is admitted to the drying chamber the target is suddenly elevated to the position shown in dot dash lines in Fig. 4, moving to such elevated position through a slot 75 in the top wall of the casing. By painting this target red or some other vivid color, it forms an excellent indicator, quickly visible from a distance.

The thermometer 64, of course, also indicates conclusion of the operation by registering the drop in temperature, but this thermometer is usually employed only for a casual checking of the actual prevailing temperature.

When the drying operation is concluded, rotation of the drum may be stopped, the door may be opened, and the load is then removed and replaced with another.

Blower 20, of course, is usually stopped while the load is being changed.

The mechanism described is of relatively simple construction, automatically limits the temperature to a desired maximum, subjects the work to the desired maximum temperature for any predetermined period of time, and then promptly cools the work so that it can be handled in unloading the machine. The temperature is readily limited to an appropriate value safe for silks, wools or any other particular character of material, and the combination of both time and temperature control makes the machine flexible in its usefulness for the drying of loads of various sizes and consisting of different materials.

Other advantages of the invention will be apparent to those skilled in the art.

What I claim is:

1. Drying apparatus of the character described comprising a work container provided with cold air and hot air supply passages, two sets of dampers disposed one set in each passage, each such set being adapted to be controllably moved between damper-open and damper-closed positions, linking means connecting both said sets for operation thereof in unison, said sets being relatively so disposed that as one set opens the other set closes, air flow producing means communicating with said container for causing flow therethrough of air received from both said passages, a reciprocable operating member operatively engaging said linking means for movement thereof as aforesaid, biasing means in constant operative engagement with said linking means whereby to urge said linking means towards hot-air-open position, movable actuating means engageable with said reciprocable operating member whereby, when actuated, to move said operating member towards hot-air-closed position, retaining means for releasably maintaining said actuating means out of operative engagement with said reciprocable operating member, and time controlled means adjacent to and effective upon said retaining means upon expiration of a preset period, for releasing said retaining means whereby to cause said actuating means to engage said reciprocable operating member, and thereby cause said operating member to move towards hot-air-closed position as aforesaid.

2. Drying apparatus as defined in claim 1, and provided with a thermostatic element movable responsive to variation in air temperature passing through said chamber, and having a part disposed adjacent to and operatively effective upon said reciprocable operating member whereby to cause said operating member to move towards hot-air-closed position when said air temperature rises to a predetermined desired maximum.

3. Drying apparatus of the character described comprising a work container provided with cold air and hot air supply passages, two sets of dampers disposed one set in each passage, each such set having rotatably mounted damper means, each said damper means having fixed therewith a crank arm, a link connecting all such crank arms for operation thereof in unison, the damper means of each set being so oriented and disposed that as one set opens the other set closes, air flow producing means communicating with said container for causing flow therethrough of air received from both said passages, a reciprocable operating member operatively engaging said linking means for movement thereof to actuate said sets of dampers, spring means connected to said link whereby to urge said link towards hot-air-open position, movable actuating means consisting of a manually operable lever having a working portion engageable with said reciprocable operating member whereby, when said lever is operated, said operating member and said link are moved towards hot-air-closed position, spring biasing means effective on said lever and tending to produce operating engagement between said lever and said operating member, toggle linkage means connected to said lever for releasably maintaining said lever out of operating engagement with said operating member, and time controlled movable tip finger means adjacent to and effective upon said toggle linkage, for releasably actuating said toggle linkage whereby to permit said lever, under the bias of its spring, to engage said operating member, and cause said link to move towards hot-air-closed position as aforesaid.

4. Drying apparatus as defined in claim 3, and provided with a thermostatic element movable responsive to variation in temperature of the air being discharged from said container, and having a part disposed adjacent to and contactable with said reciprocable operating member, whereby to contact said operating member and move it towards hot-air-closed position when said air temperature rises to a predetermined desired position.

5. Drying apparatus as defined in claim 4 wherein there is provided manually adjustable wedge means disposed between said thermostatic element part and said reciprocable operating member whereby to adjustably vary the distance between said part and said member, so as to predetermine the temperature at which said thermostat part begins to be effective on said operating member.
